UNITED STATES PATENT OFFICE

LED L. RICHARDSON, OF CLEVELAND, OHIO, ASSIGNOR TO THE CLEVELAND ROCK DRILL COMPANY

PILE-DRIVING TOOL

Application filed October 26, 1928. Serial No. 315,215.

This invention relates to improvements in tools for driving pilings of planks and similar sheathing and embraces that type of tool which is adaptable for use with fluid actuated machines such as rock drills of the hammer type.

In pile driving devices customarily in use, it has been found that the high vibratory motion of the hammer frequently causes crystallization or metal fatigue in the portion of the apparatus intermediate the shank of the tool and the anvil. This crystallization and the consequent failure of the tool occurs more frequently when the strains imposed upon the shaft of the anvil support are divergent to the medial axis of the work, as is the case when the tool is used to drive a pile which has shifted or has become tilted.

One of the objects of the invention, therefore, is to construct a pile driving tool which is capable of resisting the deleterious effects of the vibrations to which it is subjected and to provide a structure which is insusceptible to fracture when used in angulated relation with the work.

Another object of this invention is to construct a tool which is accommodative to variable positions of the work without any appreciable increase in the weight of the structure.

A further object of the invention is to provide a tool which may be readily attached or dismantled with either the rock drill or the pile.

Another object of the invention is to construct a pile driving attachment which is sturdy of structure, economic of manufacture, and which is organized to accommodate the ready renewal of fractured or worn elements.

Other objects more or less ancillary to the foregoing and the manner in which all of the various objects are realized will appear in the following description which considered in connection with the accompanying

drawings, sets forth the preferred embodiment of the invention.

In the drawings

Figure 1 is a perspective view partially in section of a rock drill including one embodiment of the improved pile driving attachment;

Figure 2 is an elevational view partially in section illustrating the construction of the pile driving attachment;

Figure 3 is longitudinal sectional view of the attachment, the section being taken on a plane indicated by line 3-3 in Figure 2;

Figure 4 is a detail elevational view of one of the elements of the pile driving tool; and

Figure 5 is a detail sectional view of the anvil for the attachment.

Referring to the construction illustrated in Figure 1 the rock drill comprises a cylinder 10 in which there is reciprocatively mounted a piston 11, co-ordinated in the usual manner with a tappet, which impels with percussive force, the coaxially aligned pile driving tool 13. The motive fluid which actuates the piston is controlled by the customary throttle 12.

The tool or pile driving attachment embodies an arm 14 upon which there is pivotally mounted a driving block or anvil 15. The arm is constructed with a shank 16, adapted for cooperative engagement with the tool chuck 17, and a swaged head portion 18, formed with a convexedly arcuate face 19, and a centrally disposed aperture 20. The anvil 15 embraces a pair of vertically disposed ears 21 which are apertured to receive a bolt 22 provided to facilitate the pivotal support of the anvil upon the arm 14. The body of the anvil intermediate the ears 21 is formed with a concavity 23 which is of complementary configuration to the arcuate face of the head 18 and which, by virtue of the clearance provided between the bolt 22 and the aperture 20 is engageable therewith. The lower portion of the anvil is bifurcated and is prefer-

ably proportioned, with respect to the thickness of the work for which it is adapted, to afford an intimate telescopic engagement of the furcations 23 with the end of the piling.

5 In the practice of this invention the anvil may be adjusted upon the end of a piling and the machine set in operation irrespective of any divergency between the axis of the work and the medial axis of the machine.

10 As the pile is being driven it may be observed that the angular relation thereof is inconsistent with the position of the other pilings in the retaining wall. In this event the operator may incline the hammer through an 15 angle opposed to the tilted position of the work and without removing the anvil or stopping the machine effectuate the correct seated position of the piling.

It will be noted that the aperture 20 being 20 enlarged with respect to the body of the bolt will permit the engagement of the arcuate face of the head 18 with the concave bearing seat 23. Thus the percussive forces transmitted through the arm will be born by the 25 anvil and the counter forces initiated by tilting the hammer will be repelled within the zone of engagement of the pile and anvil rather than through the axis of the arm as is the case in the homogeneous type of apparatus.

30 Although the foregoing description is necessarily of a detailed character in order that the invention may be completely set forth, it is to be understood that the specific 35 terminology is not intended to be restrictive or confining, and that various rearrangements of parts and modifications of structural detail may be resorted to without departing from the scope or spirit of the invention as 40 herein claimed.

I claim:

1. A pile driving tool comprising an arm and an anvil, an arcuate bearing face in said arm and a complementary bearing seat 45 in said anvil and pivotal means co-ordinated with said arm and anvil to permit the engagement of the said bearing face with the said bearing seat.

2. A pile driving tool comprising an arm 50 having a convexedly arcuate bearing face formed in a headed portion thereof, an anvil having a bearing seat of complementary configuration with the bearing face in said arm, a pivot pin supported by said anvil and 55 loosely supporting said arm.

3. A pile driving tool comprising an arm having a convexedly arcuate bearing face 60 formed in a headed portion thereof, an anvil having a bearing seat of complementary configuration with the bearing face in said arm, a pair of vertically disposed ears on said anvil, a pivot pin retained in said ears, said pivot pin loosely supporting said arm.

4. A pile driving tool comprising an arm 65 having a convexedly arcuate bearing face

formed in a headed portion thereof, an anvil having a bearing seat of complementary configuration with the bearing face in said arm, a pair of vertically disposed ears on said anvil, a pivot pin retained in said ears, said pivot pin loosely supporting said arm and dependent furcations formed in the outer face of the anvil.

In testimony whereof I hereunto affix my signature this 18th day of October, 1928.

LED L. RICHARDSON.
